ROBERT EDGAR, OF LOS ANGELES, CALIFORNIA

REMOTE CONTROL APPARATUS FOR MINIATURE BOATS

Application filed July 14, 1925. Serial No. 43,594.

My invention relates generally to miniature land and water vehicles and particularly, although not necessarily, to miniature or toy boats.

5 It is a purpose of my invention to provide a miniature boat having incorporated therein an extremely simple, practical and inexpensive apparatus which is manually operable from a point remote with respect to the 10 boat to move and control at will the movements of the boat in such manner that by skillful manipulation of the apparatus from a remote point such as the shore of a body of water a boat can be caused to describe a 15 proscribed course.

It is also a purpose of my invention to provide a remote control apparatus of the above described character which embodies instrumentalities on the boat such as sails, flags, 20 and whistles, and means by which the instrumentalities can be actuated at will by the operators while at a remote point from the boat.

I will describe only two forms of remote 25 control apparatus embodying my invention and will then point out the novel features thereof in claims.

In the accompanying drawings

Figure 1 is a view showing in side elevation 30 and partly in section a miniature boat having applied thereto one form of remote control apparatus embodying my invention.

Figure 2 is a fragmentary view showing in side elevation the bow end of the boat 35 shown in Figure 1.

Figure 3 is an enlarged fragmentary perspective view of one of the masts of the boat shown in Figure 1 and the adjacent pulley mechanism.

40 Figure 4 is a horizontal sectional view taken on the line 4—4 of Figure 1.

Figure 5 is a detail perspective view of the reel embodied in the control apparatus.

Figure 6 is a similar view showing the 45 staff which constitutes a mounting for the reel.

Figure 7 is a view showing in side elevation 50 a miniature boat having applied thereto another form of control apparatus embodying my invention.

Figures 8 and 9 are views illustrating in plan and diagrammatically a boat and its towlines as embodies in my invention showing two methods of towing.

Similar reference characters refer to similar parts in each of the several views.

Referring specifically to the drawings and particularly to Figure 1 my invention in the present embodiment is shown as applied to a miniature boat simulating a steamship 55 and having a hollow hull 15 to accommodate parts of the control apparatus, and a pair of masts 16 and 17. The control apparatus comprises a control line consisting of a suitable cord associated with the body to provide a 60 bow towline 18, the stern towline 19, and a boat line 20, the latter being associated with instrumentalities on the boat so that they can be actuated by proper manipulation of the bow and stern towlines. As shown the 65 towlines 18 and 19 are trained about pulleys 21 and 22, respectively, mounted at the bow and stern ends of the hull 15 on supports 23 pivoted in brackets 24 secured to the hull to swing about vertical axes, the supports 23 being formed with hoods 25 to prevent floating 70 particles from interfering with rotation of the pulleys. The mounting of the pulleys is such that they are free to swing in a horizontal plane whereby unrestricted rotation 75 thereof and movement of the line thereover is at all times insured. From the pulleys 21 and 22, the lines 18 and 19 extend upwardly and over pulleys 26 and 27, respectively, from whence they extend rearwardly and 80 forwardly towards the center of the hull. That portion of the line between the pulleys 26 and 27 referred to as the boatline is trained about pulley mechanisms arranged fore and aft of the hull for the purpose of actuating the 85 instrumentalities on the boat.

By reference to Figures 1 and 3, it will be clear that the boat line in its extension forwardly from the pulley 27 passes beneath a pulley 28 mounted in a bracket 29 and then 90 upwardly and around a pulley 30 mounted on the upper end of a lever 31. From the pulley 30, the boat line extends rearwardly and around a pulley 32 mounted in the same 95 bracket 29 but above the pulley 28, from 100

whence it extends upwardly alongside of the aft mast 17 and around a pulley 33 rotatably supported on the mast and provided with a hood 34. From the pulley 33 the line extends downwardly and around a pulley 35 mounted in the bracket 29. The pulley mechanism thus far described constitutes the aft pulley mechanism and is designed to actuate a flag 36 for the mast 17 and bellows 37 for a whistle 38. To actuate a second bellows 39 for the whistle 38 and a second flag 40 for the mast 16 the boat line is extended forwardly from the rear pulley mechanism for operative connection to the front pulley mechanism. As shown in Figure 1, the boat line is extended forwardly from the pulley 35 to a point beneath and above a pulley 41 mounted in a bracket 42. From the pulley 41 the line extends upwardly above a pulley 43 on the mast 16 then downwardly beneath a pulley 44 in the bracket 42, rearwardly to a pulley 45 on the upper end of a lever 46, around the latter and then forwardly to a pulley 47 in the bracket 42. From the pulley 47 the line extends forwardly to the pulley 26.

From the foregoing description, it will be clear that the two pulley mechanisms are practically identical and consequently the operation in connection with the flags and pulleys will be identical, and as the construction of the bellows, the actuated means therefore, the flags in their supporting means are identical, a description of one will suffice for both. As shown in Figure 3 the flag 36 is supported on a pair of arms 48 and 49, the arm 48 being secured to a clamp 50 and the latter in turn embracing the adjacent vertical stretch of the boat line so that the flag and its supporting means are secured to the boat line to be moved vertically therewith. The arm 49 is provided at its inner end with a loop member 51 through which the boat line loosely extends, the clamp 50 is provided with an arm terminating in a hook 52 which loosely receives the other vertical stretch of the boat line, thus it will be seen that the members 51 and 52 co-operate in holding the flag in a fixed vertical position with respect to the bow line and mast so that the flag will at all times extend lengthwise from the boat so as to be readily viewed from either side of the boat.

In the foregoing mounting of the flag 36, it will be clear that the flag can be adjusted vertically with relation to the mast by vertical movement of the boat line, but in practice the flag is adapted to occupy the position shown in Figure 3 which is the uppermost position or a lower position in which it is adjacent the deck of the boat. By reference to Figure 1 it will be clear that the flag 40 is associated with the bow line operable in the same manner as the flag 36, and in practice the two flags are adapted to be poised and lowered together.

The bellows 39 is arranged on one end of a pipe 53 having openings 54 which constitute the whistle 38, and in surrounding relation to the openings 54 is a relatively large pipe 55 which functions to direct the sound upwardly through imitation smoke stacks 56. The pipe 55 is provided with a cap 57 at its upper end which serves to prevent water from being discharged into the pipe and thus interfering with the operation of the whistle. The bellows 37 is normally engaged by rounded head 58 mounted on a yoke 59 (Figure 4) with the latter slidably in guide bars 60. The yoke 59 is operatively connected to the lever 31 through a link 61 and the lever is pivoted at its lower end as indicated at 62 to the bottom of the hull 15. The lever 31 through actuating the boat line is adapted to be moved in the normal position shown in Figure 1 toward the bellows 37 thereby imparting a corresponding movement to the head 58 to compress the bellows and thereby discharge air through the openings 54 to sound the whistle. The bellows 39 is provided with an identical mechanism and the lever 31 thereof is connected to the first lever 31 through a spring 63 in such manner that the spring operates to yieldingly retain the two levers in the normal position shown in Figure 1. By this arrangement the two levers can be simultaneously moved in opposite directions upon actuation of the boat line to move their heads into compressing relation to the bellows 37 and 39 so that the latter cooperates in actuating the whistle as will be understood.

As illustrated in Figures 8 and 9, the bow and stern towlines are of sufficient length to extend the desired distance from the bow and stern ends, respectively, of the boat, and to facilitate manipulation of these lines they are trained about a reel 64. As shown in Figure 5, the towlines are reversely trained about the reel so that by rotating the reel in one direction or the other one towline or the other will be wound or unwound from the reel so as to exert a pulling or slackening action upon the line which is necessary in the control of the boat. In Figure 1 I have shown a staff 65 adapted to be held in the hand of the operator and provided with a reduced end 66 upon which the tubular reel 64 is mounted. This staff is of sufficient length to permit the desired elevation of the reel and towlines to avoid any entanglements with obstructions between the boat and the operator.

In operating the instrumentalities through the medium of towlines let it be assumed that the boat is afloat in a body of water and the operator is at some remote point preferably on the shore. By the operator now exerting a pull on the bow line 18 at the same time slackening the stern line 19, the boat line 20 will be pulled in the direction of the bow line thus effecting the hoisting of the two flags to the

elevated position shown in Figure 1. Conversely, upon exerting a pull on the stern line and slackened the bow line the flags will be lowered to a position adjacent the deck. By exerting a minimum pull equally upon the two towlines the flags will be held against movement and in any position within the range of their adjustment. Upon increasing the pull beyond this minimum the resistance offered by the air bellows and the springs will be overcome thereby actuating the levers 31 to move the heads 58 to compress the bellows and thus sound the whistle. On slackening both towlines equally and together the levers can be returned to normal position without lowering the flags, as will be understood.

In the manipulation of the towlines for moving and controlling movement of the boat, it is necessary that any movement of the towlines be executed slowly and without jerking thereof less the flags and whistle be actuated. It is best first to consider the two towlines at equal angles with respect to the boat. In this position of the towlines the operator by slowly and equally pulling on both lines at the same time will drag the boat sideways in the water and toward him. However, should the bow line be at a greater angle with respect to the boat than the stern line as illustrated in Figure 8 then by pulling on both lines as before the boat will travel ahead. Should the position of the towlines be reversed, it will be clear that by exerting an equal pull on the line that the boat will travel astern. If the operator pulls slowly and steadily upon both lines with the pull on the bow line slightly greater than that on the stern line the boat's bow will be turned towards the operator. The resistance offered by the pulleys prevent a slightly increased pull from actuating the instrumentalities on the boat. By reversing the manner of pulling it will be manifest that the boat's stern will be turned in the direction of the operator and without actuating the instrumentalities. In all these movements the operator can readily alter the angle of his boat and lines by simply rotating the staff in the direction suitable to the angle required.

When it is desired to shift the boat and the towlines from their respective positions in towing ahead in any given direction to their corresponding positions for towing ahead in the opposite direction, or from their respective positions in towing astern in any given direction to their corresponding positions for towing astern in the opposite direction, the towlines in each instance have to be changed from one side of the boat to the other as has been illustrated diagrammatically in Figures 8 and 9. To accomplish this two methods are employed which I term the direct and indirect and which have been clearly illustrated in Figures 8 and 9, respectively. In either method one of the tow-

lines must be passed beneath the hull of the boat and to facilitate such an operation such line is weighted with a small sinker 67 in spaced relation to the boat so that when such line is released it will be submerged sufficiently for the purpose. The line to be weighted depends upon which of the two methods of changing the side of control is adopted by the operator for each respective class of towing. If desired both lines may be weighted to suit either method.

Assuming that the boat is beyond the reach of the operator and his staff recourse must be had to either of the two methods, and the farther the boat is out from the shore the more skill is required in the manipulation of the towlines to change the side of control. It is believed to be obvious from the diagrammatical illustrations in Figures 8 and 9 as to the manipulation of the towlines in carrying out the two methods referred to.

Referring now to Figure 7, I have here shown a sail boat to which is applied another form of remote control apparatus which is similar to the first apparatus in that a control line is provided to form bow and stern towlines 68 and 69, respectively, and a boat line 70. The towlines are associated with the hull of the boat in a manner identical with that shown and described in connection with the first form of control apparatus, the boat line 70 is associated with a gib sail 71 and a main sail 72 in such manner as to effect upon operation of the boat line a lowering or elevating of the two sails. As shown, the main sail is secured at its bottom edge to a swinging gib 73 the latter being formed at its forward end with a ring 74 slidably fed on a mast 75. The rear end of the gib 73 is secured to a staple 76 fixed in the deck of the boat so as to hold the gib in a fixed horizontal plane at the same time allowing of limited lateral movement thereof to permit the sail to swing to one side or the other of the mast. The main sail 72 at its upper end is secured to the boat line 70 so that by vertical movement of the boat line the sail can be lowered or elevated. The gib sail 71 is connected at its forward end to a front gib 77 secured to the bow of the boat. The rear end of the gib sail is tied to a staple 78 fixed in the deck, and at its top corner a suspension cord is run up and made fast to another stretch of the boat line 70.

The boat line 70 can be traced as extending rearwardly from the front pulleys 26 to and around a pulley 79 mounted on the deck of the boat. From the pulley 79 the boatline extends upwardly and around a pulley 80 mounted on the upper end of the mast 75. From this pulley the line extends downwardly around a pulley 81 mounted on the lower end of the mast. From the pulley 81 the line extends upwardly around a pulley 82 mounted on the upper end of the mast, and from

thence downwardly around a pulley 83 also mounted on the mast. From this pulley 83 the line extends rearwardly to the pulley 27.

From the arrangement as described it will be seen that on pulling the bow line 68 and slackening the stern line 69, the two stretches of the boat line 70 to which the sails 71 and 72 are connected will be pulled downwardly and the two sails thus lowered. Conversely, on pulling the stern line and slackening the bow line, the two stretches of the boat line attached to the sails will be moved upwardly thus elevating the sails. The two towlines 68 and 69 are adapted to be associated with the reel 64 in the same manner as described in the first form of control apparatus and thereby manipulated in a like manner to move and control the movements of the sail boat.

Although I have herein shown and described only two forms of remote control apparatus for miniature boats embodying my invention, it is to be understood that various changes and modifications may be made therein without departing from the spirit of the invention and the spirit and scope of the appended claims.

What I claim is:

1. A boat having a pair of masts, a pneumatic signal on the boat, a pair of bellows for actuating the signal, a pair of heads movable to compress the bellows, a pair of levers operatively connected to the heads and normally urged to a position in which the bellows are expanded, a control line, pulleys on the boat and masts for supporting the control line for movement on the masts and for operatively connecting the line to said levers, the ends of the control line extending from the ends of the boat, and flags secured to the control line for movement vertically of the masts, the mounting of the control line being such that by pulling both ends of the control line the signal will be sounded through actuation of said heads and by pulling one end or the other of the control line the flags will be lowered or elevated with respect to said masts depending on which end of the line is pulled.

2. A boat having a control line connected thereto to provide bow and stern towlines and a boat line; signals on the boat operatively connected to the boat line; and means for supporting the boat line for movement to actuate the signals upon manipulation of the towlines.

3. A boat having masts, flags capable of being raised or lowered on the masts, and a control line connected to the boat to provide bow and stern towlines and a boat line operatively connected to the flags so that by manipulation of the towlines the flags can be raised or lowered on the masts.

4. A boat having a control line connected thereto to provide bow and stern towlines and a boat line, whistles on the boat, bellows

for sounding the whistles, and elements movable to compress the bellows operatively connected to the boat line so as to be actuated thereby upon predetermined movement of the towlines.

5. A boat having signals thereon, and a control line connected to the boat to provide bow and stern towlines by which the boat can be moved and the movements thereof controlled, and a boat line operatively connected to the signals and associated with the towlines so that the signals can be actuated without controlling the movement of the boat.

6. In combination, a boat having bow and stern tow lines, a reel about which the lines are reversely trained so that when the reel is rotated in one direction or the other one line or the other will be wound on the reel and the other line unwound from the reel, and a staff upon which the reel is secured to rotate therewith and by which the lines can be supported in elevated position to permit one to pass the lines over obstacles between the boat and reel in following or controlling the movements of the boat when in water.

7. In combination, a toy or miniature boat having bow and stern tow lines, and a member supporting the tow lines in reversely wound relation and operable to permit manual manipulation of the lines in elevating the latter and the winding of one line and the simultaneous unwinding of the other.

8. In combination, a boat having a bow and stern tow lines, a member about which the lines are reversely trained so that when the member is rotated in one direction or the other one line or the other will be wound on the member and the other line unwound therefrom, and collars arranged in spaced positions on the member to receive therebetween the reversely trained lines in a manner to preclude winding of the lines upon each other and slipping of the lines off the member.

9. A boat having a mast, a signal capable of being raised or lowered on the mast, and a control line movable in relation to the boat and providing a bow tow line, a stern tow line and a boat line, the boat line being operatively connected to the signal so that by manipulation of the tow lines the signal can be raised or lowered on the mast.

10. A toy or miniature boat having a bow towing line and a stern towing line connected to the extreme ends of the boat and extending forwardly and obliquely at one side of the boat, so that in towing ahead the bow line is at a greater angle with respect to the boat than the stern line whereby upon towing the boat by the lines from the shore the boat will advance at an angle and thus define a course spaced from the shore.

ROBERT EDGAR.
